UNITED STATES PATENT OFFICE.

EDITH A. B. BURT, OF SPRINGFIELD, MASSACHUSETTS.

REENFORCEMENT FOR BUTTONHOLES.

Application filed September 18, 1922. Serial No. 588,938.

To all whom it may concern:

Be it known that I, EDITH A. B. BURT, citizen of the United States, residing at Springfield, in the county of Hampden and 5 State of Massachusetts, have invented new and useful Improvements in Reenforcements for Buttonholes, of which the following is a specification.

This invention relates to improvements in 10 reinforcements for button holes, eyelets, and the like.

An object of the invention is to provide a reenforcement which is sufficiently rigid to properly strengthen the button hole or eyelet 15 and which is also capable of yielding to conform to the shape of the shank of the button or hook that may be inserted in the reenforced button hole.

Another object of the invention is the 20 provision of a reenforcement which is simple in construction and that is capable of being economically manufactured and which is also capable of being readily and easily attached to the button hole.

With the above objects in view, my invention will be described with particular reference to the accompanying drawings in 25 which—

Fig. 1 is a plan view of my improved reenforcement;

Fig. 2 is a plan view showing one manner of securing the reenforcement to a piece of fabric;

Figs. 3 and 4 are front and side elevational views respectively, showing a hook inserted within the reenforced button hole; and

Fig. 5 is a view showing a modified form of reenforcement.

In the practice of my invention I preferably provide a reenforcement that comprises a material such as wire or the like that is bent or formed into the shape of a closed loop. The ends 2 and 3 of the band are 45 preferably overlapped and unjoined as in Fig. 1 to permit a relative movement of the ends when the band is distorted as will later appear.

While I have shown the band formed in 50 the shape of circular loop it is apparent that the reenforcement may be formed in the shape of an oval or rectangular loop or other shape depending upon the style or shape of button hole or eyelet that it may be 55 desired to reinforce and I therefore do not limit myself to the form shown.

One method of securing the reenforcement to a fabric is shown in Fig. 2 in which figure *f* represents a piece of fabric provided with a button hole or eyelet *o*. The 60 reenforcement is placed to encircle the opening *o* and may be secured therearound by button hole or over-stitching as indicated by *s*. The method or means of securing the reenforcement to the fabric forms no 65 part of the present invention, the method shown being merely for the purpose of disclosing the invention in its present preferred form.

It will be observed that when the reenforcement is secured to the fabric around the button hole that the button hole is rigidly reenforced around its entire edge and that the button hole and its reenforcement may be distorted to an elongated shape 70 and that such distortion by reason of the overlapped unjoined ends of the reenforcement permits the button hole and reenforcement to yield to an appreciable extent since the overlapped ends of the reinforcement are 75 permitted to move relative one to the other.

For the purposes of illustrating the action of my reenforcement when under strain reference may be had to Fig. 3 in which figure *a* a fabric 4 is shown that carries a 80 button or hook member 5. A fabric 6 is shown that is provided with a button hole or eyelet 7 to which is applied my reenforcement 1. As will be observed the fabrics are shown as being under a strain in opposite directions which straining actions causes the shank of the hook 5 to distort or elongate the button hole without impairing the functioning of the reenforcement since the ends thereof are arranged for a relative 85 sliding movement.

The amount of overlap of the reenforcement band ends may be varied as is desired and is more or less dependent upon the use for which the band is to be used. That is to say, the overlap is in accordance with the degree of distortion to which the reinforced button hole is to be subjected.

Where the reenforcement is not to be subjected to any appreciable distortion the form 105 shown in Fig. 5 I have found to be of considerable advantage. In this form the reenforcement comprises a circular ring of yieldable material that may be secured to fabric in a manner similar to that shown in 110 Fig. 2. This band 8 when secured to the fabric is yieldable within reasonable limits

and may easily be distorted without impairing its usefulness as a reenforcement.

While I have shown the reenforcements in the forms as at present preferred it is obvious that many changes may be made in their construction without departing from the scope of my invention and I therefore prefer to be limited by the appended claims rather than by the foregoing description.

10 I claim:

1. A reenforcement for buttonholes comprising, a member formed into the shape of a loop having unjoined end portions, the said end portions being arranged in an overlapping relation and formed to coincide

with the contour of the loop, whereby they are adapted for a relative sliding movement to allow an expansion of the loop with the end portions in their overlapping relation.

2. A reenforcement for button-holes comprising a metal member formed in the shape of a circular loop, the ends of the said member being arranged in an overlapping unjoined contiguous relation and terminating at their overlapping portion and arranged for a relative movement whereby the said loop may expand when under strain.

In testimony whereof I have affixed my signature.

EDITH A. B. BURT.
